COMBINED COMB, TOOTHBRUSH, AND TOOTHPASTE RACK

Joe A. Di Tirro, Cleveland, Ohio, assignor to Marianna Corporation, Cleveland, Ohio, a corporation of Ohio

Filed Aug. 23, 1963, Ser. No. 76,346

Term of patent 14 years

(Cl. D4—3)

FIG. 1

FIG. 2

FIG. 3

FIG. 4

FIG. 5

FIG. 6

FIG. 7

FIG. 1 is a perspective view of a combined comb, toothbrush, and toothpaste rack, showing my new design; FIG. 2 is a top plan view thereof;

FIG. 3 is a cross-sectional view taken along the line 3—3 of FIG. 4;

FIG. 4 is a side elevational view;

FIG. 5 is a front elevational view;

FIG. 6 is a reduced rear elevational view; and

FIG. 7 is a reduced bottom view thereof.

The elements shown in broken lines in FIG. 1 are included for illustrative purposes only.

I claim:

The ornamental design for a combined comb, toothbrush, and toothpaste rack, as shown and described.
